REPEATER-CIRCUITS.

1,382,631.

Specification of Letters Patent. Patented June 28, 1921.

Application filed May 17, 1919. Serial No. 297,902.

To all whom it may concern:

Be it known that we, CHARLES S. DEMAREST and SAMUEL P. SHACKLETON, residing at Brooklyn and New York, in the counties of 5 Kings and Bronx and State of New York, respectively, have invented certain Improvements in Repeater-Circuits, of which the following is a specification.

This invention relates to transmission circuits and more particularly to transmission circuits in which repeaters are employed.

One of the objects of this invention is to simplify the apparatus and reduce the expense connected with the installation of repeater equipment for telephone lines. Another object of the invention has reference to the provision of means whereby one repeater may be employed for a plurality of connecting circuits. Other and further objects of the invention will more fully appear in connection with the detailed description hereinafter given.

Where cord circuit repeaters are employed in the establishing of connections between long distance transmission lines, it is customary to provide a repeater unit for each repeater cord at each position. Under certain circumstances, however, it is desirable that the same operating unit be used 30 for repeater cords at two positions so that the amount of apparatus necessary may be reduced. The repeater unit comprising the amplifiers, relays, coils, etc., is usually arranged at a point some distance from the 35 switchboard and is connected with the switching cords and controlling keys such as the listening, splitting and repeater control keys by means of a series of conductors extending from the repeater unit to the switchboard 40 position. These conductors are of two kinds, those used for transmission purposes and extending to the plugs or other switching arrangements of the cords, and those used merely for control or supervisory purposes and leading to the several controlling 45 keys. In accordance with the present invention the apparatus is so arranged that the controlling conductors leading from the repeater unit may be switched into connection with conductors leading to the controlling keys at either of two switchboard 50 positions. The transmission conductors leading to the plugs or other switching means at the switchboard positions are connected in parallel to the two positions. Means are

provided whereby when the operator at one position utilizes a repeater cord at that position in establishing a connection, the controlling conductors leading from the repeater unit are switched into connection with the 60 controlling keys of that cord without disturbing the parallel connections to the switching plugs at both positions. By this arrangement of the apparatus the operator who first establishes a connection has complete control over the repeater and while 65 it is possible for the operator at the other position to attempt to set up a connection, substantially no harm can result therefrom since the operator cannot by means of the 70 controlling keys interfere with the connection already established and cannot by means of her listening set obtain access to the connection which she attempted to establish. The association of additional lines 75 with the lines already connected does not result in unbalancing the repeater and causing singing for the reason that artificial lines are associated with the circuit at the same time. In order, however, to prevent 80 the possibility of an operator attempting to set up an additional connection of this character a busy lamp is caused to glow at the other switchboard position when the first connection is established in order to indicate 85 that the repeater is already in use.

The invention may now be more fully understood by reference to the following description when read in connection with the accompanying drawings, Figures 1 and 2 of 90 which constitute a circuit diagram of one embodiment of the invention.

Referring to the drawing, a repeater organization of the well known two-way two repeater type including amplifiers A and A' 95 is illustrated. This repeater may be associated with either of two switchboard positions designated as X and Y upon the drawing. In order to interconnect toll lines through the repeater, the operator at position X is provided with cords terminating in twin plugs P₁ and P₂ adapted to cooperate with twin jacks of toll lines. In a similar manner the operator at position Y is provided with cords terminating in plugs 100 P'₁ and P'₂. In order that the repeater shown in Fig. 2 may be used in establishing connections at either switchboard position, the incoming line conductors L and the corresponding artificial line conductors N of 110

the repeater are connected in parallel over conductors L_1 and L_1' and conductors N_1 and N_1' to the incoming twin plugs P_1 and P_1' at the two positions. In a similar manner the outgoing conductors L' and N' are connected in parallel over conductors L_2 and L_2' and over conductors N_2 and N_2' to the outgoing twin plugs P_2 and P_2' .

Normally the repeater is not included in circuit with the incoming and outgoing conductors leading to the switching plugs at either position to the incoming line. Conductors L are connected to the line conductors L' through a direct connection including conductors C and C' . The conductors C and C' may be interconnected either through conductors C_1 , C_2 and the contacts of the splitting key K_2 at position X or through conductors C_1' and C_2' and the contacts of 20 the splitting key K_2' at position Y .

In order to exercise control over the connections which may be established at position X through the repeater, the operator at that position is provided with a listening key K_1 and a repeater control key K_3 in addition to the splitting key K_2 already referred to. In a similar manner the operator at position Y is provided with listening key K_1' and repeater control key K_3' in addition to the splitting key K_2' . The various control circuits which will be hereinafter described as extending from the repeater to the several keys at each operator's position are arranged to pass over the contacts of a series of switching relays 1, 2 and 3. Normally the cord circuit conductors C and C' as well as the control circuit conductors are extended over the back contacts of these switching relays to the keys K_1 , K_2 and K_3 at position X . When the switching relays are energized however, the cord circuit connections as well as the controlling circuit connections are shifted from the keys at position X to the corresponding keys at position Y .

In order to effect the switching of these circuits by means of the switching relays a double wound relay 4 is provided in the sleeve circuits of the plugs P_1 and P_2 at position Y so that when either or both of these plugs are inserted in line jacks the relay 4 will be energized to effect the shifting of the connections. A similar relay 5 is provided in the sleeve circuits of the plugs P_1 and P_2 at position X . The circuit of the relay 5 is rendered inoperative when the relay 4 is energized. In a similar manner when the relay 5 is energized by inserting either or both of plugs P_1 and P_2 in line jacks, the circuit of 60 the relay 4 is rendered inoperative so that the switching relays 1 to 3 inclusive will remain in their normal condition with the cord conductors and controlling circuits switched to position X .

The transmission connections extending 65 from the repeater to the line and artificial line contacts of the plugs at the two positions in parallel are at no time affected by the transfer of the circuit control from one position to the other. This avoids transmission losses which might result from the additional relay contacts which would have to be provided in these transmission connections if they were to be shifted from one position to the other. 75

In order to prevent any possibility of confusion arising from one operator at one position attempting to set up a connection when the repeater is already employed in a connection set up at the other position, busy lamps 6 and 7 are provided for the two positions so that when a connection is established at one position the busy lamp at the other position will be caused to glow, indicating to the operator at that position that the apparatus is already in use. 85

Should the operator at one position ignore the busy lamp and insert the plugs in the jacks of toll lines, no harm would result so far as the repeater is concerned even though 90 the two connections were crossed since the operator upon inserting the twin plug in the jack connects a suitable balancing network to the repeater at the same time that the toll line is connected to the repeater consequently even though two lines be connected in parallel to each end of the repeater, the repeater will still remain balanced and sing- 95 ing will not result.

By placing the controlling circuits under 100 the control of the operator who first established the connection, the second operator will be unable to interfere with the connection established by the first operator by manipulating any of her controlling keys and 105 will be locked out from the circuit even though she actuates her listening key. The provision of busy lamps is sufficient to prevent any confusion between the operators except in very infrequent instances and in 110 such instances the shifting of the control circuits without interference with the transmission circuits is sufficient to insure against any harmful results.

Further details of the apparatus may now 115 be understood from a description of the operation which is as follows:

Assuming that the operator at position X desires to set up connection between two toll lines through the repeater shown in Fig. 2, 120 the plug P_1 will be inserted in the jack of the incoming line thereby completing a circuit from the grounded sleeve contacts of said jack over sleeve contacts of the plug P_1 through the left hand winding of relay 125 5 and over the right hand back contact of relay 4 to battery. A parallel circuit is established at the same time over the grounded

- sleeve contacts of the jack, sleeve contacts of the plug P_1 , inner left hand back contact of relay 4 and over conductor 8 through the winding of relay 9 to battery.
- 5 Relay 5 upon being energized disconnects battery at its left hand contact from the windings of relay 4 thereby preventing the energization of said relay due to the operator at station Y attempting to establish 70 a connection through the plugs P_1' and P_2' . Relay 5 at its left hand front contact completes a circuit from battery over conductor 10 and through the busy lamp 7 to ground thereby causing the lamp to glow 75
- 10 a to indicate to the operator at position Y that the repeater is already in service. Relay 5 by opening its right hand contacts disconnects the sleeve conductors of plugs P_1' and P_2' from the sleeve relays 9 and 12. The switching relays 1, 2 and 3 are under the control of the relay 4 and as this relay has been rendered inoperative by the relay 5 the switching relays cannot be affected by any attempt of the operator at 80
- 15 position Y to set up a connection.
- 20 25 Returning to relay 9 whose circuit was completed by inserting the plug P_1 in the line jack, the energization of said relay results in the completion of a circuit from ground over the lower front contact of said relay to point 13 from which point the circuit extends over conductors 14 and 15, back contacts of ringing responsive relays 16 and 17 in series and over conductor 18 through 95
- 30 the winding of relay 19 to battery. Relay 19 is energized over the circuit above described and by opening its right hand contact prevents the energization of relay 20 which would otherwise result from the connection of ground to the point 13.
- 35 40 A direct connection now extends between the line contacts of plugs P_1 and P_2 over conductors L_1 and L , back contacts of relay 21, conductors C, back contacts of relay 3, conductors C_1 , normal right hand contacts of splitting key K_2 , conductors 22, normal left hand contacts of splitting key K_2 , conductors C_2 , back contacts of relay 2, conductors C' , back contacts of relay 23 and 100
- 45 50 over conductors L' and L_2 to plug P_2 . The operator by actuating the listening key K_1 may bridge her set across the transmission path above traced at points 24 and 25.

55 In order to complete the connection to the outgoing transmission line, the operator may insert the plug P_2 in the jack of the outgoing transmission line and operate the repeater control key K_3 . A circuit is completed from the grounded sleeve contacts 115 of the outgoing line jack over the sleeve contacts of the plug P_2 through the right hand winding of relay 5 and over the right hand contact of relay 4 to battery. This circuit is without effect as relay 5 had already been energized through its left hand 120

60 65 winding. A parallel circuit is completed over the sleeve contacts of plug P_2 over the left hand contact of relay 4 and through the winding of relay 12 to battery. Relay 12 is therefore energized and at its lower contact connects ground to point 13 in parallel with the ground connected over the contact of relay 9. The actuation of the repeater control key K_3 completes a circuit for the filament control relay 29 from battery through the winding of said relay over conductor 30, right hand back contact of relay 3 over conductor 31, right hand make contact of key K_3 , over conductors 32, 33 and 14 to point 13 and thence to ground over the lower front contacts of relays 9 and 12. The energization of relay 29 over the circuit above traced results in the completion of the filament circuit from battery B' through the filaments of the amplifiers A and A' rendering the tubes operative. The actuation of the repeater control key K_3 also results in completing a circuit from grounded point 13, over conductor 34, right hand back contact of relay 1, conductors 35 and 36, also normal right hand and left hand contacts of splitting key K_2 , right hand normal contact of listening key K_1 , conductor 37, inner left hand back contact of relay 1, conductor 38, upper front contacts of relays 9 and 12, conductors 39 and 40, left hand make contact of key K_3 , conductors 41, 42 and 43 through the winding of relay 44, back contact of relay 45 over conductor 46 and thence in parallel through the windings of relays 21 and 23 to battery. Relays 44, 21 and 23 are energized over the circuit above traced, the former operating to open the short circuit normally existing about the primaries of input transformers 105 47 and 48 of the repeater and to connect said transformers to input bridges 49 and 50 of the repeater. Relays 21 and 23 operate to disconnect the line conductors L and L' from the cord conductors C and C' 110 and to connect the repeater in circuit.

55 60 With the circuit in the condition just described, transmission from the incoming line passes over conductors L_1 and L over the front contacts of relay 21, through the input bridge 49 and input transformer 47 through the amplifier A, where the variations are amplified, to the output circuit 115 53 and transformer 52. At the transformer the energy divides, part flowing to the outgoing line over the front contacts of relay 23 and conductors L' and L_2 , and part flowing to the artificial line over conductors N' and N_2 . In a similar manner transmission from the outgoing line passes over conductors L_2 and L' over the front contacts of relay 23 to the input bridge 50 and input transformer 48 through the amplifier A' to the output circuit 54 and output transformer 51 where the energy divides, part 120

65 70 75 80 85 90 95 100 105 110 115 120 125 130

- flowing over the front contacts of relay 21 and conductors L and L₁ to the incoming line and part flowing over conductors N and N₁ to the artificial line.
- 5 If, with the circuit in this condition, ringing current should be transmitted from the incoming line, the ringing current will flow over conductors L¹ and L to ringing responsive relay 17 which will be actuated to open 10 the circuit previously traced through relay 19. Relay 19 is accordingly deenergized and completes a circuit from grounded point 13 over the back contact of relay 19 and through the winding of relay 20 to battery.
- 15 Relay 20 at its right hand front contact completes a circuit for relay 45 which may be traced from grounded point 13 over conductor 34, right hand back contact of relay 1, conductors 35 and 36, lower normal contacts 20 of the splitting key K₂, right hand normal contact of listening key K₁, conductor 37, inner left hand back contact of relay 1, conductor 38, upper front contacts of relays 9 and 12, conductors 39 and 40, left hand make contact 25 of key K₃, conductors 41, 42 and 55, front right hand contact of relay 20 and through the winding of relay 45 to battery. Relay 45 upon being energized opens the circuit previously traced through relays 44, 30 21 and 23 and at its front contact completes a holding circuit for relays 21 and 23 from ground over conductor 46 and through the windings of said relays to battery. Relay 44 is deenergized and again short circuits 35 the input windings of the transformers 47 and 48 to prevent ringing current from being transmitted to the repeater.
- Returning to relay 20, said relay at its left hand front contact completes a circuit from 40 grounded point 13 over the left hand front contact of relay 20 through the winding of relay 56 to battery. Relay 56 completes a locking circuit over its upper front contact over conductors 57 and 58, left hand normal contact 45 of key K₁, conductors 59 and 35, right hand back contact of relay 1 to grounded point 13. At its lower front contact relay 56 completes a circuit from ground over conductor 60, left hand back contact 50 of relay 1 and through the lamp 61 to battery. The lamp 61 now glows to indicate to the operator that a ring has come in from one of the toll lines.
- The operator may now actuate the listening key K₁ which, by opening its left hand contact, breaks the locking circuit of relay 56 with the consequent effacement of the lamp 61. Key K₁ by opening its right hand contact breaks the circuit previously traced 60 to relay 45 which is deenergized and again connects relay 44 in circuit with relays 21 and 23. The original circuit of these relays, however, it will be remembered, passes over the right hand contact of the key K₁ so that 65 relays 21 and 23 are now deenergized in ad-
- dition to the relay 44. The deenergization of relays 21 and 23 results in again interconnecting the line conductors L and L' through the cord connection including conductors C, C', the splitting key K₂ and conductors C₂ 70 and C₁. The operator's set is now bridged across this circuit and the operator upon ascertaining that the call came in from the incoming line may, if she desires, throw the splitting key K₂ to the left thereby disconnecting the outgoing end of the circuit so that her set will remain connected to the incoming line to the exclusion of the outgoing line.
- If, with the circuit in the condition just 80 described, ringing current should be transmitted over the outgoing line, the transmitted ringing current would pass over conductors L₂ and L' to the ringing responsive relay 16 thereby again opening the circuit 85 of the relay 19 which was, of course, restored as soon as relay 17 ceased to respond to ringing current. Relay 19 again closes the circuit of relay 20 which again completes the circuit of relay 56 but does not cause 90 the energization of relay 45 as the circuit of the latter relay is held open at the contacts of the listening and splitting keys. A locking circuit for relay 56 is completed over the upper front contact of said relay over 95 conductors 57, 58 and 62, lower left hand make contact of splitting key K₂, lower right hand normal contact of said key over conductors 36 and 35, right hand back contact of relay 1 and over conductor 34 to grounded 100 point 13. Relay 56 again completes the circuit of the lamp 61 whereupon the operator is informed that a call has come in over the outgoing line.
- The operator may then throw the splitting key to the right thereby disconnecting the incoming line from the circuit and leaving her set bridged across the outgoing line. The actuation of the splitting key momentarily opens the locking circuit above traced 105 for relay 56 which is accordingly deenergized and effaces the lamp 61. Should the operator restore the listening key K₁ and the splitting key K₂ to normal, the circuit originally traced for relays 44, 21 and 23 110 would be again completed so that the repeater is again rendered operative and is connected in the transmission circuit.
- Should the operator desire to take down 120 the connection she will withdraw plugs P₁ and P₂ from the line jacks and restore the key K₃ to normal. The withdrawal of the plugs P₁ and P₂ breaks the circuits through both windings of relay 5 and through the relays 9 and 12 so that these relays are restored to normal. The lamp 7 is effaced by the deenergization of relay 5 and battery 125 is again connected to the windings of relay 4. The deenergization of relays 9 and 12 removes the ground connection from point 130

- 13 so that relays 19, 29, 44, 21 and 23 are de-energized it being remembered that the circuits of all of these relays pass to ground through point 13. The apparatus is now 5 in a normal condition and ready for the completion of a connection at either position X or position Y.
- It will be noticed with reference to the connection described as having been set up 10 at the position X, that the various circuits controlled by keys K_1 , K_2 and K_3 extended from the repeater to said keys over the back contacts of switching relays 1, 2, and 3. Alternative connections are provided to the 15 keys K_1' , K_2' , and K_3' at position Y but these connections are inoperative since they are maintained open at the contact of the switching relays, 1, 2 and 3. The operator at position Y is therefore unable to control 20 the repeater or in any way change the condition of the connection established at position X by manipulating her controlling keys. Should the operator at position Y fail to observe the busy lamp 7 and insert 25 either or both of the plugs P_1' and P_2' in the jacks of toll lines, the toll lines in question will be connected in parallel with the toll lines interconnected through the repeater at position X. However, at the same time 30 suitable balancing artificial lines are connected in parallel to the artificial lines involved in the connection at station X so that the repeater is not unbalanced and therefore does not sing. The operator at position Y 35 is unable, by throwing her listening key, to bridge her set across the connection and will therefore realize that the repeater is in use and will withdraw the plugs inserted in the toll line jacks.
- 40 With the apparatus restored to normal as above described, the operator at position Y may establish a connection through the repeater at Fig. 2 by employing the plugs P_1' and P_2' . The insertion of the plug P_1' in 45 the jack of the incoming line completes a circuit over the sleeve contacts of the plug through the left hand winding of relay 4 to battery. A circuit is also completed over the sleeve contacts of the plug and over the 50 inner right hand contact of relay 5 and over conductor 8 through the winding of relay 9 to battery. Relay 4 at its right hand contact disconnects battery from the windings of the relay 5 thereby rendering the latter 55 inoperative and at its right hand front contact relay 4 completes a circuit from battery to the busy lamp 6 to indicate to the operator at position X that the repeater is in use. By opening its left hand contacts, 60 relay 4 disconnects relays 9 and 12 from the sleeve conductors of plugs P_1' and P_2' . Relay 4 at its right hand front contacts also completes a circuit from battery over conductor 63 and through the windings of relays 1, 2 and 3 in parallel to ground. These 65

relays upon being energized shift the connections which normally extend to keys K_1 , K_2 and K_3 at position X to the keys K_1' , K_2' and K_3' at position Y.

Relay 9 at its lower front contact upon 70 being energized completes the previously traced circuit of the relay 19 which holds open the circuit of the relay 20. A transmission connection now exists from the incoming line over the left hand tip and ring contacts of the plug P_1' over conductors L_1' and L , back contacts of relay 21, conductors C , front contacts of relay 3, conductors C_1' , over the normal contacts of splitting key K_2' , over conductors C_2' , front 80 contacts of relay 2, conductors C' , back contacts of relay 23 and over conductors L' and L_2' to the right hand tip and ring contacts of plug P_2' . The operator by throwing listening key K_1' may bridge her set 85 across the transmission circuit above traced.

In order to complete the connection, the operator will insert the plug P_2' in the jack of the outgoing line and throw the repeater control key K_3' , the listening key K_1' being 90 restored to normal. A circuit is completed over the sleeve conductor of the plug P_2' through the right hand winding of relay 4 and over the back left hand contact of relay 5 to battery but as relay 4 is already energized this circuit is without effect. A circuit is also completed over the sleeve conductor of the plug P_2' and over the right hand back contact of relay 5, over conductor 11 and to the winding of relay 12 to battery. 100 Relay 12 at its lower contact now connects ground to point 13 in parallel with the ground applied to said point over the lower contact of relay 9.

A circuit for the filament control relay 29 105 is completed from battery through the winding of said relay over conductor 30, right hand front contact of relay 3, conductor 31', right hand make contact of key K_3' over conductors 32', 33 and 14 to grounded point 110 13. A circuit is also completed for relays 44, 21 and 23 from grounded point 13 over conductor 34, front right hand contact of relay 1, conductors 35' and 36', over the lower normal contacts of key K_2' , over the right hand 115 normal contact of listening key K_1' , over conductor 37', inner left hand front contact of relay 1, conductor 38, upper front contacts of relays 9 and 12, conductors 39 and 40', left hand make contact of key K_3' , conductors 41', 42 and 43 through the winding of relay 44 over the back contact of relay 45, over conductor 46, through the windings of relays 21 and 23 to battery. The energization of relays 29, 44, 21 and 23 results in the 125 same certain changes as already described with reference to the connection established at position X.

With the circuit in this condition, transmission from the incoming line passes over 130

conductors L_1' and L , over the front contacts of relay 21 through input bridge 49, transformer 47 and amplifier A to output circuit 53 and outgoing transformer 52 where the energy divides, part being transmitted over the front contacts of relay 23 and conductors L' and L_2' to the outgoing line and part being transmitted over conductors N' and N_2' to the artificial line. In a similar manner transmission incoming from the outgoing lines passes over conductors L_2' , L' and the front contacts of relay 23 through input bridge 50 and transformer 48 and through amplifier A' of the repeater to the outgoing transformer 51 where the energy divides, part being transmitted over the front contacts of relay 21 and conductors L and L_1' to the incoming line and part being transmitted over conductors N and N_1' to the corresponding artificial line.

Should ringing current be transmitted over the incoming line the relay 17 will be energized to open the circuit of relay 19 which, in turn, completes the circuit of relay 20 in a manner already described. Relay 20 at its right hand front contact completes the circuit of relay 45 over a path extending from grounded point 13 over conductor 34, right hand front contact of relay 1, conductors 35' and 36', lower normal contacts of the splitting key K_2' , right hand normal contact of listening key K_1' to conductor 37', inner left hand front contact of relay 1, conductor 38, upper front contacts of relays 9 and 12, conductors 39 and 40', left hand make contact of key K_3' , conductors 41', 42 and 55 over the right hand front contact of relay 20 and through the windings of relay 45 to battery. The energization of relay 45 produces circuit changes similar to those already described with reference to the connection set up at position X.

Relay 20 at its left hand front contact completes the circuit of relay 56 which is locked up over a circuit extending over its upper front contact over conductors 57 and 58' over the left hand normal contact of key K_1' , over conductors 59' and 35', right hand front contact of relay 1 and over conductor 34 to grounded point 13. At its lower front contact relay 56 completes a circuit from ground over conductor 60, left hand front contact of relay 1 and through the lamp 61' to battery. The glowing of lamp 61' indicates to the operator that a ring has been transmitted over one of the connected lines. The operator may then actuate her listening key which causes the deenergization of relay 56 thereby effacing the lamp 61'. The actuation of the listening key also opens the circuit of relay 45 and causes a deenergization of relays 21 and 23 in addition to relay 44. The two toll lines are now directly interconnected through the cord circuit connections including conductors C, C_1' ,

C_2' , C' and the splitting key K_2' and the operator's set is bridged across the connection. The operator may upon ascertaining that the ring originated on the incoming line, throw the splitting key K_2' to the left thereby being enabled to communicate with the incoming line to the exclusion of the outgoing line. 70

If, with the circuit in this condition, ringing current was transmitted from the outgoing line, ringing responsive relay 16 would be actuated to again restore the slow release relay 19 which in turn completes the circuit of relay 20. The energization of relay 20 does not complete the circuit of relay 45 as the circuit of said relay is held open at the contacts of the keys K_1' and K_2' . The circuit of relay 56, however, is completed at the left hand front contact of relay 20 and relay 56 at its upper front contact 85 establishes a locking circuit over conductors 57, 58' and 62', over the lower left hand make contact of splitting key K_2' , over the lower right hand normal contact of said key, over conductors 36' and 35', right hand front contact of relay 1 and over conductor 34 to grounded point 13. Relay 56 completes the circuit of the lamp 61' thereby indicating to the operator that a ring has come in from the outgoing line. The operator 95 may then throw the splitting key to the right in order to communicate over the outgoing line to the exclusion of the incoming line. The operation momentarily opens the locking circuit of relay 56 which is deenergized 100 and effaces the lamp 61'.

As soon as the operator restores the listening and splitting keys K_1' and K_2' respectively, the circuit of relays 44, 21 and 23 is again completed so that the repeater is once 105 more rendered operative and is again connected in the transmission circuit previously described. The connection may be taken down by withdrawing plugs P_1' and P_2' and restoring the repeater control key K_3' . Relays 4, 9 and 12 are deenergized upon withdrawing the plugs. The deenergization of relay 4 restores switching relays 1, 2 and 3 to normal and the deenergization of relays 9 and 12 by disconnecting ground from 115 point 13 restores relays 19, 29, 44, 21 and 23 to normal.

It will be observed that under the conditions just described the connections from the repeater to the controlling keys K_1' , K_2' and K_3' at position Y were wholly under the control of the operator at said position and the corresponding connections to the keys at position X were held open so that the operator at the latter position was unable to 125 control the repeater or in any manner affect the connection established at position Y. Should the operator at position X disregard the busy lamp and attempt to connect to a transmission line, she would therefore be 130

unable to listen in on the line and even though the line be connected in parallel with a line involved in the connection established at position Y, the repeater would not be unbalanced for the reason that a corresponding artificial line would be connected in the circuit at the same time.

By means of the arrangement above described, the same repeater may be used for establishing connections at two positions thereby eliminating a certain amount of apparatus with a consequent reduction in the expense involved in the installation.

It will also be observed that the general principles herein disclosed may be embodied in many other organizations widely different from that illustrated without departing from the spirit of the invention as defined in the following claims.

20. What is claimed is:

1. In a signaling system, a repeater, a plurality of lines, a plurality of sets of switching apparatus for associating the repeater with a line, parallel transmission connections extending from said repeater to each set of switching apparatus, keys associated with each set of switching apparatus for controlling the functioning of the repeater, and means whereby when the repeater is associated with a line by one set of switching apparatus the repeater will be rendered independent of the controlling keys of another set of switching apparatus without disturbing said parallel transmission connections.

2. In a signaling system, a repeater, a plurality of switch board positions, lines terminating at said positions, parallel transmission connections extending from said repeater to each position over which said repeater may be associated with lines at that position, controlling keys at each position, connections whereby the control of the repeater can be extended to the keys at any one of the positions, and means whereby when the repeater is associated with a line at one position the connections from the repeater to the corresponding controlling keys will be established and the repeater rendered independent of other controlling keys without disturbing said parallel transmission connections.

3. In a signaling system, a repeater, a plurality of switch board positions, lines terminating at said position in jacks, cords at each position terminating in plugs adapted to cooperate with said jacks, parallel transmission connections extending from the repeater to the plugs at different positions, controlling keys at each position, connections whereby the control of the repeater may be extended to the controlling keys at any one of the positions, and means responsive to the insertion of the plugs at one position in the jack of a line at that position to

establish a connection from the repeater to the controlling keys at that position and render the repeater independent of keys at another position without disturbing the parallel transmission connections to other plugs. 70

4. In a signaling system, a repeater, a plurality of switch board positions, lines terminating at said positions in jacks, cords at each position terminating in plugs adapted to cooperate with said jacks, parallel transmission connections extending from the repeater to the plugs at different positions, controlling keys at each position, connections normally extending from the repeater to the controlling keys at one position, and means whereby when a plug at another position is inserted in the jack of a line at that position the repeater is disconnected from the keys at the first position and connected to the keys at the second position without disturbing the parallel transmission connections of other plugs. 80

5. In a signaling system, a repeater, a plurality of lines, a plurality of sets of switching apparatus for associating the repeater with a line, parallel transmission connections extending from said repeater to each set of switching apparatus, keys associated with each set of switching apparatus for controlling the functioning of the repeater, 95 busy signals associated with each set of switching apparatus, and means whereby when the repeater is associated with a line by one set of switching apparatus the repeater will be rendered independent of the controlling keys of another set of switching apparatus without disturbing said parallel transmission connections, and whereby a busy signal associated with said other set of switching apparatus will be operated. 100

6. In a signaling system, a repeater, a plurality of switch board positions, lines terminating at said positions, parallel transmission connections extending from said repeater to each position over which said repeater may be associated with lines at that position, controlling keys at each position, connections whereby the control of the repeater can be extended to the keys at any one of the positions, busy signals at each 110 position, and means whereby when the repeater is associated with a line at one position the connections from the repeater to the corresponding controlling keys will be established and the repeater rendered independent of other controlling keys without disturbing said parallel transmission connections, and whereby a busy signal at another position will be operated. 115

In testimony whereof, we have signed our names to this specification this 16th day of May, 1919. 125

CHARLES S. DEMAREST.
SAMUEL P. SHACKLETON.
